FIG. 5 is a top view of the first embodiment;

FIG. 6 is a bottom view of the first embodiment;

FIG. 7 is a first side view of the first embodiment;

FIG. 8 is a second side view of the first embodiment;

FIG. 9 is a front perspective view of a second embodiment of a mobile electronic device housing;

FIG. 10 is a back perspective view of the second embodiment;

FIG. 11 is a front view of the second embodiment;

FIG. 12 is a back view of the second embodiment;

FIG. 13 is a top view of the second embodiment;

FIG. 14 is a bottom view of the second embodiment;

FIG. 15 is a first side view of the second embodiment; and,

FIG. 16 is a second side view of the second embodiment.

The broken lines shown in the drawings represent portions of the mobile electronic device housing that form no part of the claimed design.
